UNITED STATES PATENT OFFICE.

ADOLPH R. SWOBODA, OF MONTCLAIR, NEW JERSEY, ASSIGNOR, BY MESNE ASSIGNMENTS, TO WESTERN ELECTRIC COMPANY, INCORPORATED, A CORPORATION OF NEW YORK.

POLARIZED REPEATING SOUNDER.

1,265,830.

Specification of Letters Patent. Patented May 14, 1918.

Application filed September 13, 1915. Serial No. 50,376.

To all whom it may concern:

Be it known that I, ADOLPH RUDOLPH SWOBODA, a citizen of the United States, residing at Montclair, in the county of Essex 5 and State of New Jersey, have invented certain new and useful Improvements in Polarized Repeating Sounders, of which the following is a full, clear, concise, and exact description.

10 This invention relates to telegraph sounders, and more particularly to a polarized repeating sounder.

The object of this invention is to provide a new and improved form of polarized repeating sounders of few and simple parts readily adjustable and efficient in operation.

In accordance with one feature of this invention, a simple and efficient means is provided for adjusting and maintaining the 20 position of a permanent magnet relative to the core of an electromagnet. Preferably this is accomplished by having one end of the permanent magnet pivoted so that the free ends thereof may be swung toward and 25 away from the ends of the cores by adjustable means located at the opposite end of the permanent magnet.

In accordance with another feature of this invention, means are provided for applying 30 contact springs to a sounder of standard construction without modification of the standard construction of the device. Means are also provided for readily adjusting the springs without changing their position with 35 relation to each other.

This invention is illustrated in the accompanying drawings in which the same reference characters are used throughout to designate the same parts, and in which Figure 1 is 40 a top view of a polarized repeating sounder embodying this invention. Fig. 2 is a side elevation, partially in section, of the device shown in Fig. 1. Fig. 3 is an end elevation, partially in section, of the device shown in 45 Fig. 1. Fig. 4 shows in detail a contact spring assembly and the method of mounting it. Fig. 5 shows details of the permanent magnet and associated parts.

As shown in the drawings, the polarized 50 repeating sounder comprises a base 6 with an opening 7 therein, over which is mounted a plate 8 which is attached to the base by means of screws 9 (only one screw shown in

drawings). On plate 8 is mounted a pair of electromagnets 10, 10. The soft iron cores 55 11, 11 of the electromagnets have their lower ends reduced in diameter and a shoulder is thereby formed which engages plate 8. In plate 8, holes are drilled through which the reduced ends of the cores pass. The ends of 60 the soft iron cores are drilled and tapped for the reception of screws 12, 12 which form extensions of the cores 11, 11. Screws 12 clamp the plate and cores together.

On plate 8 is also mounted a trunnion 65 bracket 13 which carries a trunnion 14 engaging the sounding bar 15. At the top of trunnion bracket 13 is a fixed plate 17 carrying a lock-nut 18 and adjusting screw 19 which engages one end of sounding bar 15 70 by means of spring 20 and tends to hold the sounding bar in its normal position. Near the middle of sounding bar 15 is rigidly attached an armature 21 which is attracted by means of the magnetism induced in the cores 75 of the electromagnets. On the sounding bar 15 is mounted a lock-nut 22 and an adjusting screw 23 for limiting the downward stroke of the bar.

An insulating contact pin 24 is carried by 80 arm 25, which is fixed at one end of sounding bar 15 by means of screws 26, 26. Sounding bridge 27 is attached to and supported by plate 8. On the arm of the sounding bridge is mounted a lock-nut 28 and an 85 adjusting screw 29 for limiting the upward stroke of the sounding bar.

On the sounding bridge 27 is pivotally supported a bifurcated bracket 30 carrying a contact spring assembly 31 which is rigidly 90 mounted thereon. The master spring of the contact spring assembly engages the insulating contact pin 24 and by movement of the sounding bar 15, which carries said contact pin, make-and-break connections are 95 made between the master spring and the associated springs. The contact spring assembly mounted on the bifurcated bracket is adjusted by means of spring 32, nut 33 and screw 34 which engages arm 35 of the bifurcated bracket and by turning the nut 33 the contact spring assembly may be separated from or brought in contact with the contact insulating pin 24.

For polarizing the cores of the electro- 105 magnets there is mounted on the under-

neath side of the base 6, a permanent U-shaped magnet 36. The legs of this magnet have bent-over portions 37, 37 which are at an angle of approximately 180 degrees with respect to the main portion of said magnet 5 and rest against a non-magnetic bar 38, which serves as a pivotal point for movement of said permanent magnet. The bent-over portions 37, 37 lie within the opening 7 of the base 6 with the free ends adjacent to the cores of the electromagnet. The non-magnetic bar 38 lies in groove 39 which runs transversely in plate 8, and in groove 40 which runs transversely in the turned-over portion of said permanent magnet. The bent-over portions 37, 37 of the magnet 36 are held against the bar 38 by means of a semi-circular clamping rod 41 and screw 42. The threaded portion of screw 42 passes 20 through a hole in the semi-circular clamping bar between the legs of the permanent magnet and engages the metal base 8. By means of the longitudinal adjustment of threaded sleeve 43 engaging screw 44, both of which are located at the closed end of the 25 U-shaped permanent magnet, the air gap between the ends of the cores of the electromagnet and the free ends of the permanent magnet is adjusted.

30 A double-throw switch is represented by 45 and a set of contact terminals by 46, both of which are mounted on the base 6.

It will be noticed that by mounting the contact pin on an extension of the sounder bar and adjustably mounting the contact spring assembly on the sounding bridge, simple and reliable means are afforded for adjusting the springs of a repeating sounder without changing the position of the springs 35 with respect to each other. It will further be noticed that by mounting the permanent magnet with the turned over portions of its legs lying in the opening of the base adjacent the ends of the cores of the electromagnets with one end of the permanent magnet pivoted and adjusting means at the 40 other end, the air gap between the cores of the electromagnets and the free ends of the permanent magnet may be readily adjusted 45 and maintained.

50 What is claimed is:

1. In a polarized sounder, a base, an electromagnet carried by said base, a permanent magnet carried by said base and having 55 its free ends adjacent the cores of said electromagnet, and means for adjusting the position of said permanent magnet to vary the air-gap between it and the cores of the electromagnet.

60 2. In a polarized sounder, a base, an electromagnet mounted thereon, a U-shaped permanent magnet mounted on said base with its ends adjacent the ends of the cores of said electromagnet, a pivotal support for 65 said permanent magnet, and means for mov-

ing said permanent magnet about said pivotal support to vary the air-gap between said permanent magnet and the cores of said electromagnet.

3. In a polarized sounder, a base, an electromagnet mounted on said base, a U-shaped permanent magnet having its legs turned over at the ends, means for supporting said permanent magnet on the base with the ends of the turned-over portions adjacent the ends of the cores of the electromagnet, a pivotal member against which said permanent magnet bears, and means engaging the closed end of said permanent magnet to move it about its pivot to vary the air-gap between the ends of said permanent magnet and the cores of said electromagnet. 75

4. In a polarized sounder, a base having an opening therethrough, an electromagnet mounted upon one side of said base with its cores adjacent said opening, a U-shaped permanent magnet pivotally supported upon the opposite side of said base and having the ends of its legs turned over and located in the opening of said base adjacent the cores of the electromagnet, and means for swinging said permanent magnet about its pivotal support for adjusting the air-gap. 80

5. In a polarized sounder, an insulating base having an opening therethrough, a metal base mounted upon said insulating base, an electromagnet mounted upon its metal base with the lower ends of its cores adjacent the opening in said insulating base, a U-shaped permanent magnet having its legs turned back upon themselves, means for supporting said permanent magnet from said metal base with the turned-over portions within the opening in said insulating base adjacent the cores of the electromagnet, 95 a pivotal member between said metal base and said permanent magnet, and means for swinging said permanent magnet about said pivotal member to vary the distance between the ends of said turned-over portion 100 and the cores of said electromagnet. 105

6. In a polarized sounder, an insulating base having an opening therethrough, a metal base mounted upon said insulating base and provided with a groove extending transversely thereof, an electromagnet mounted upon said metal base with the lower ends of its cores adjacent the opening in said insulating base, a U-shaped permanent magnet having its legs turned back upon themselves and provided with transversely extending grooves in said turned-over portions, means for supporting said permanent magnet from said metal base with the turned-over portions within the opening in said insulating base adjacent the cores of the electromagnet, a pivotal member lying in said grooves between said metal base and said permanent magnet, and means for swinging said permanent magnet about 110 115 120 125 130 135

said pivotal member to vary the distance between the ends of said turned-over portion and the cores of said electromagnet.

7. In a polarized sounder, an insulating base having an opening therethrough, a metal base mounted upon said insulating base, and provided with a transversely extending groove, an electromagnet mounted upon said metal base with the lower ends of its cores adjacent the opening in said insulating base, a U-shaped permanent magnet having its legs turned back upon themselves and having grooves extending transversely of said turned-over portions, a semi-circular clamping member, means for engaging said semi-circular member for supporting said permanent magnet from said metal base with the turned-over portions within the opening in said insulating base adjacent the cores of the electromagnet, a non-magnetic pivotal pin lying in said grooves between said metal base and said permanent magnet, and means for swinging said permanent magnet about said pivotal pin to vary the

distance between the ends of said turned-over portion and the cores of said electromagnet.

8. In a repeating sounder, an electromagnet, a sounder bar controlled thereby, a spring contact controlling device carried by said sounder bar, a bridge, and a contact spring assembly adjustably supported on said bridge in operative relation to said spring contact actuating device.

9. In a repeating sounder, an electromagnet, a sounder bar controlled thereby, a spring contact controlling device carried by said sounder bar, a bridge, a pivotally supported bracket on said bridge, a contact spring assembly carried by said bracket and coöperating with said spring contact controlling member, and adjusting means for said bracket.

In witness whereof, I hereunto subscribe my name this 10th day of September, A. D. 1915.

ADOLPH R. SWOBODA.
